UNITED STATES PATENT OFFICE.

WILLIAM THOMAS, OF BEATRICE, NEBRASKA.

HOISTING-BUCKET.

1,200,274.

Specification of Letters Patent.

Patented Oct. 3, 1916.

Application filed September 9, 1915. Serial No. 49,683.

To all whom it may concern:

Be it known that I, WILLIAM THOMAS, a subject of the Emperor of Germany, and a resident of Beatrice, in the county of Gage 5 and State of Nebraska, have invented a new and Improved Hoisting-Bucket, of which the following is a full, clear, and exact description.

My invention relates to a hoisting device 10 designed particularly for the purpose of receiving grain or similar loose material from a wagon from which it is unloaded, and conveying the material into a crib, granary, bin or similar storage receptacle, and the 15 object thereof is to provide a particular construction of hoisting bucket into which the grain or other material is permitted to run, after which the bucket is hoisted by means of a suitable hoisting rope and is caused to 20 travel along a track provided in the granary or building into which the material is to be transported and wherein it is stored.

The particular features of construction 25 wherein my invention consists will be hereinafter referred to in detail as the same is described.

With the above and other objects in view, my invention consists in the improved grain 30 hoisting bucket and hoisting means therefor illustrated in the accompanying drawings described in the following specification and particularly claimed.

Referring now to the drawings wherein the preferred embodiment of my invention 35 is illustrated, Figure 1 is a view showing my improved hoisting bucket in side elevation and showing also the hoisting and controlling ropes associated therewith; Fig. 2 is a view illustrating the hoisting bucket and 40 the ropes for hoisting and controlling the same, and a track arranged within a building into which the material is to be carried; Fig. 3 is a view showing a section of my improved hoisting bucket upon a horizontal 45 plane indicated by the line 3—3, Fig. 1, looking down; Fig. 4 is a view of my improved hoisting bucket taken upon a vertical central plane indicated by the line 4—4, Fig. 3; and Fig. 5 is a view showing a section 50 taken upon a plane at right angles to the plane of Fig. 4, and upon a vertical plane indicated by the line 5—5, Fig. 4, looking toward the left.

Referring now to the drawings, the reference numeral 7 designates two parallel 55 supporting bars spaced apart from one an-

other and which bars support the bucket and through which the same and its contents are lifted when the bucket is in use, these bars being preferably of channel iron form, as 60 shown in Fig. 5.

Supported from the ends of the cross bars or supports 7 are four vertically arranged bars 8 preferably of angle iron form as shown, to which bars are riveted or otherwise 65 secured the sheet iron ends 9 of the bucket, suitable diagonal braces 10 being preferably provided for stiffening the framework formed by the members above referred to and holding the vertical members 8 and 70 horizontal members 7 at a proper angle with reference to one another, as will be understood.

The reference numerals 11 designate angle iron bars, four of such bars being provided, 75 the same being secured by rivets or otherwise to the sides of the iron ends 9 of the bucket, as will be understood from Fig. 3, and to which angle iron corners the ends of the sides 12 of the bucket are secured, as will also 80 be understood from Fig. 3, these sides being preferably made up of a plurality of boards, as shown in Figs. 4 and 5. One or more of the upper boards are preferably easily removable in order to vary the height of the 85 side of the bucket so that it may be readily adapted for use with wagons having their bottoms different heights from the ground. The side of the bucket body can be placed under the rear end of the wagon body from 90 which the grain or other material is to be unloaded into the bucket. I preferably provide two pieces of angle iron 38 at the tops 95 of the sides for protecting the edges of the top side boards, as best shown in Fig. 1.

The sides and ends above referred to constitute an open-bottom structure or body portion, rectangular in form, and supported through the vertical bars 8 and transverse bars 7 and capable of being lifted thereby, 100 and the open bottom of this bucket body is closed by two swinging bottom sections or doors 13, the inner edges of which overlap when the bottom of the bucket is closed, as shown in Figs. 1 and 3, and which doors are 105 so supported from the body of the bucket that in opening they move for the most part in a lateral direction, see Fig. 4, the vertical movement of the meeting edges of the doors being comparatively slight.

The doors or bottoms 13 are preferably formed of sheet metal and are provided with

upwardly extending flanges 14 at their sides and back which inclose the lower edge of the bucket body when the doors are in their closed position, as shown in Fig. 1. The doors 13 are pivotally supported by means of bars 15, 16, a pair of bars being provided at each end of each of the swinging doors 13. The upper ends of these bars are pivotally supported on the body of the bucket adjacent the ends thereof, as shown at 17, suitable brackets 18 being provided for the upper ends of the pivotal supports, while the lower ends of said bars are bolted or riveted to the doors 13 at points 19 adjacent the opposite ends thereof. It, therefore, follows, because of the fact that the pivots 17 about which the doors swing are located some distance up from the lower edge of the bucket body and adjacent the ends thereof, that a movement of the doors in opening is for the most part lateral with reference to the body of the bucket and that the vertical movement of the doors is comparatively slight even at the free meeting edges thereof, at which point the vertical movement is the greatest.

The reference numeral 20 designates two gates located one at each side of the bucket, said gates being secured to one of the swinging doors or bottoms 13 so as to be carried thereby, by means of rivets 21. The gates 20 partake of the swinging movement of the door to which they are secured, as will be understood from Figs. 1 and 4, and as the doors swing into their open position, drop below the lower edge of the bucket, and serve to guide the material as it passes from the bucket and to prevent the material from escaping sidewise, as will be understood.

The reference numeral 22 designates a retarding bar shown as angular in form and extending from side to side of the bucket, the ends of which are supported in an adjustable manner from the sides of the bucket, as will be understood from Fig. 4, wherein a plurality of holes 23 are shown as provided in one of the sides through various of which holes the bolts 24 may be passed, which bolts support the retarding bar through right angle brackets 25. The purpose of this retarding bar is to retard the flow of material from the bucket when the doors are in their open position, and, in order to retard the flow of material to a still greater extent, which is sometimes desirable in dealing with fine material such as grain, shelled corn, etc., I contemplate using retarding wings 26, four of such wings being shown. The wings 26 are pivotally supported from the retarding bar 22 so that when the doors 13 are in their closed position, the wings may swing up into the position illustrated in dotted lines, Fig. 4, in which case their free edges rest upon the doors 13. When the doors are open, the re-

tarding wings swing into the lowermost position in which they are illustrated in full lines, in which case their lower edges occupy positions close to the upper surface of the doors 13. The retarding wings are supported from the retarding bar 22 by means of angular extensions 27 provided at the upper ends of bars 28 secured to the retarding wings, and which extensions extend through openings 29 provided in the retarding bar 22, as shown in Fig. 4. This construction, it will be appreciated, permits the retarding wings to fold when the doors are closed and provides a stop for limiting the downward movement of the wings as the free end of the bent portion 27 contacts with the inner surface of the angular retarding bar 22. It will be seen that these wings may be removed entirely from the bar by swinging them upward and withdrawing the angular extensions 27 through the openings 29. The purpose of the retarding bar and wings, as explained, is to retard the flow of material from the bucket, the degree of retardation being variable by adjusting the retarding bar and by using therewith retarding wings, as many as may be found desirable. In cases where it is not deemed necessary to retard the flow of material from the bucket, the entire retarding mechanism may be removed as it is secured in place, as above explained, in such a way as to be easily detachable and removable from the bucket body.

The inner or meeting edges of the doors 13 are supported and the doors held in their closed position by means of centrally located bars 30, the lower ends of which are pivotally connected with the doors through brackets 31 and the upper ends of which bars are pivotally connected with a vertically movable cross head 32, which cross head is adjustably secured to a trip bolt 33 having a head 34, which head is engaged by a trip lever 35 when the doors are closed, as shown in Fig. 1, and which trip lever may be operated to release the trip bolt, as shown in Fig. 4, when the doors are permitted to open to discharge the contents of the bucket.

It will be understood from the construction above described that the doors may properly be referred to as self-closing, and that the mere act of setting the bucket upon the ground will close the doors and permit the latch 35 to engage the head 34, thus locking the doors in their closed position.

The cross head 32 has been referred to as adjustable, it being obvious that by loosening the screws 36 carried by the cross head, the cross head may be moved up and down upon the trip bolt 33 in order to so adjust the parts that the doors will be closed properly against the lower edge of the bucket when the head 34 is engaged by the latch 35.

35. The opening in the cross head through which the trip bolt 33 passes is enlarged at its ends and contracted to contact with the trip bolt intermediate its ends at 37, see 5 Fig. 4, from which it will be obvious that the screws 36 may be manipulated in such a way as to tip the cross head with reference to the trip bolt. The purpose of this feature is to permit the doors to be so adjusted 10 that they will close close against the lower edge of the bucket body, this being accomplished by adjusting the cross head vertically, and furthermore to permit of adjustment so that the overlapping edges of the 15 doors will properly contact with one another, this being accomplished by tipping the cross head, if necessary, upon the bolt by means of the screws 36 after its vertical position is properly determined, such tipping 20 motion serving to move the overlapping edges of the doors toward or from one another, as will be appreciated.

The reference numeral 39 designates a guide and stop member through which the 25 lower end of the trip bolt 33 extends, the ends of which stop member are supported by means of bars 40, the upper ends of which are supported from the cross bars 7, the connection between the ends of the stop 30 member 39 and the bars 40 being adjustable in order that the vertical position of the stop member may be varied, this adjustment being secured by means of a plurality of holes 41 provided in the supports 40 35 through any of which holes the bolts which secure the guide 39 to the supports may pass.

A spring 42 surrounds the trip bolt 33 and is interposed between the cross head 32 and the guide 39 so that as said cross head 40 moves downward after the trip bolt has been released by the latch 35, its movement is cushioned through the spring referred to. The purpose of making the guide 39 adjustable is to provide for varying the opening 45 movement of the doors 13, as it is obvious that the lower the position of said guide, the greater will be the opening movement of the doors in question.

The reference numeral 43 designates a 50 swivel sleeve made in two parts and held in position between the transverse bars 7 by means of bolts 44, and 45 designates a swivel through which the bucket is lifted and which swivel is rotatable within the swivel 55 sleeve 43 above referred to, the said swivel having a longitudinal opening 46 into which the upper end of the trip bolt 33 hereinbefore referred to extends and by which the head of said bolt is guided. The swivel in 60 question is provided with a collar 47 which contacts with the under side of the swivel sleeve 43, and which collar is provided with one or more projections 48, which obviously may enter any of a plurality of recesses 49 65 provided in the swivel sleeve for the pur-

pose of receiving the same. It follows, therefore, from this construction that when the latch 35 is in the disengaging position shown in Fig. 4, the swivel may be moved down within its sleeve to bring the projection or lug 48 out of engagement with the recess in which it rests, after which the swivel can be rotated and the projection in question brought into position to engage another recess, the purpose of which is to permit the bucket to be hoisted and advanced in four different angular positions with reference to the swivel, the angular position of which remains constant, so that either side or either end of the bucket may be made the advancing portion as the bucket moves along the track provided for it in the building in which the material being transported is to be stored.

The swivel 45 and bucket are lifted 85 through a pulley 50 by means of a lifting rope 51. The pulley is supported from the swivel through straps 52 and in such a way that the axis of the pulley is located slightly to the right (referring to Fig. 4) of a vertical line passing through the axis of the opening 46.

53 designates a balance rope, the lower end of which is secured in an opening provided in a lug 54, and which opening is to the left of the axis of the opening 46 in the swivel. This balance rope is provided with a counterbalance 55, see Fig. 2, and the fact that the axis of the pulley is to one side of the axis of the opening 46, and that the strain due to the counterbalance acting through the balance rope 53 acts upon the opposite side of said axis, tends to keep the swivel in a single plane, that is, to prevent the swivel from rotating about a vertical 105 axis and insures that the trip lever 35 will move in a straight line during the horizontal travel of the bucket, as distinguished from perhaps moving from side to side, which is a feature of importance, as in devices of the kind to which my invention relates the trip lever is often operated by a fixed stop which the lever might miss if the swivel should rotate as the bucket travels horizontally. Referring still to Fig. 2, my 110 improved bucket is intended to be used in connection with a carrier 56 adapted to move along a horizontal track 57 and into a building in which the material is to be stored, although the track and carrier form 120 no part of my present invention. While, as stated above, the trip lever 35 may be operated by a fixed stop, it may also, and in the drawings in fact is shown as being operated by means of a rope 58, and upon being operated, the doors 13 open and the contents of the bucket are discharged as above explained.

The doors 13 are preferably provided with stiffening bars 59 located adjacent their 125

meeting edges so as to keep the bottoms of the doors from sagging, they being commonly made from comparatively thin sheet metal.

5 While I illustrate and describe herein a mechanism carrying out the inventive idea in what I believe to be the most suitable form, it is to be understood that the several parts of the device may be made of any 10 suitable materials, and the relative sizes and proportions, as well as the general design of the mechanism, may be varied to a considerable extent without departing from the spirit of the invention hereafter claimed.

15 I claim:—

1. In a hoisting bucket, the combination of a bucket body, lifting means therefor, connections between the lifting means and the bucket comprising a swivel sleeve and a 20 lifting swivel extending through the sleeve, the swivel sleeve and swivel being adapted for relative rotary adjustment, and means serving to fix said relatively rotary members from rotation.

2. In a hoisting bucket, a swivel sleeve having a plurality of recesses in its lower end, a lifting swivel extending through said sleeve and rotatable therein and which sleeve is provided with a lug adapted to 30 enter any one of the recesses aforesaid; and lifting means operatively connected with said swivel.

3. In a hoisting bucket, the combination with a body portion having an opening and 35 closure means for the same, of a vertically movable cross head; connections between said cross head and said closure means; a trip bolt with which said cross head is connected; a lifting swivel having a vertically 40 extending opening into which the upper end of said trip bolt extends; lifting means connected with said swivel; and a latch carried by said swivel and adapted to engage the upper end of said trip bolt to thereby hold 45 said closure means in closed position.

4. In a hoisting bucket, a lifting swivel having a vertically extending opening; lifting means operatively connected with said 50 swivel to one side of the axis of said opening; a lug projecting in the opposite direction from the axis of said sleeve; a balance rope, one end of which is connected with said lug; and a counterbalance connected with the other end of said balance rope.

5. In a hoisting bucket, a lifting swivel rotatable about a vertical axis; a swivel sleeve through which said swivel extends; a lifting pulley operatively connected with 55 said swivel, the axis of said pulley being

offset to one side of the axis of said swivel; 60 a lug carried by said swivel and projecting therefrom in a direction opposite to the direction in which the axis of said pulley is offset; a balance rope, one end of which is secured to said lug; and a counterbalance 65 to which the opposite end of said rope is secured.

6. In a hoisting bucket, the combination of the bucket body, lifting means therefor, a swivel sleeve connected to the bucket, a 70 lifting swivel extending through the sleeve and adapted to be rotated therein around a vertical axis, said lifting means being connected to the swivel, and means coöperating with the swivel and the swivel sleeve serving to lock the same from relative rotation around the vertical axis at any desired points.

7. In a hoisting bucket, a body portion having an open bottom, closure means for 80 the bottom opening, a device connected to the closure means to hold the same closed, said device including a vertically movable cross head, a bar between the cross-head and closure means, an adjustable trip bolt connected to the cross head, a lifting swivel in which said trip bolt is movable vertically and a latch carried by the swivel coöperating with said trip bolt.

8. In a hoisting bucket, the combination 90 of a receptacle having an opening, movable means to close said opening, a lifting member connected to the top of the bucket, devices extending between the lifting member and the closing means to hold the latter 95 closed, hoisting means connected to the lifting member at one side of the vertical axis thereof and counterbalance means connected to said lifting member on the opposite side of the center thereof.

9. In a hoisting bucket, the combination of a receptacle body, a swivel sleeve connected to the receptacle, a lifting swivel journaled within the sleeve and adapted to move relatively thereto around a vertical 105 axis, means between the sleeve and the swivel to determine a fixed relation between them as to rotation, a lifting pulley connected to the swivel, the axis of the pulley being offset to one side of the vertical axis 110 of the swivel, a lifting rope coöperating with the pulley, and counterbalance means connected to the swivel on the opposite side of the axis thereof from the axis of the pulley.

WILLIAM THOMAS.
